LADY'S TRAVELING KIT

Cecilia Therrien Auger, Rouyn, Quebec, Canada

Application January 17, 1949, Serial No. 269
In Canada November 5, 1948

Term of patent 7 years

(Cl. D58—12.6)

To all whom it may concern:

Be it known that I, Cecilia Therrien Auger, a citizen of the Dominion of Canada, residing at Rouyn in the District of Rouyn-Noranda and Province of Quebec have invented a new, original, and ornamental Design for a Lady's Traveling Kit, of which the following is a specification, reference being had to the accompanying drawings, forming part thereof.

I claim:

The ornamental design for a lady's traveling kit, as shown.

CECILIA THERRIEN AUGER.
